UNITED STATES PATENT OFFICE

149,632

DESIGN FOR A LAVATORY

Warren B. Green, Darien, Conn., assignor to
Sears, Roebuck and Co., Chicago, Ill., a corpora-
tion of New York

Application December 28, 1946, Serial No. 135,822

Term of patent 14 years

(Cl. D4—2)

To all whom it may concern:

Be it known that Warren B. Green, citizen of the United States and resident of Darien, in the county of Fairfield and State of Connecticut, has invented a new, original, and ornamental Design for a Lavatory, of which the following is a specification, reference being had to the accompanying drawing, forming a part thereof.

Fig. 1 is a plan view of my new lavatory design;

Fig. 2 is a front elevational view of the same.

Fig. 3 is a side elevational view of the same; and

Fig. 4 is a transverse sectional view taken approximately on line 4—4 of Fig. 1.

I claim:

The ornamental design for a lavatory, as shown.

WARREN B. GREEN.
